UNITED STATES PATENT OFFICE.

PERCY H. HOWARD, OF CAMBRIDGE, MASSACHUSETTS.

DESIGN FOR A FRONT PLATE FOR HEADLIGHTS.

51,970.

Specification for Design.

Patented Apr. 16, 1918.

Application filed January 26, 1917. Serial No. 144,790. Term of patent 14 years.

To all whom it may concern:

Be it known that I, PERCY H. HOWARD, a subject of Great Britain, residing at Cambridge, in the county of Middlesex and State of Massachusetts, have invented a new, original, and ornamental Design for a Front Plate for Headlights, of which the following is a specification, reference being had to the accompanying drawing, forming part thereof.

The figure is a front view of a front plate for headlights, showing my new design.

I claim:

The ornamental design for a front plate for headlights, as shown.

PERCY H. HOWARD.

Witnesses:

B. J. NOYES,
H. B. DAVIS.
